CLAIM

The ornamental design for the antenna base, as shown and
described.

DESCRIPTION

FIG. 1 is a top, front, and right side environmental perspective view of a antenna base, showing our new design with
the broken line structure being for illustrative purposes only
and forming no part of the claimed design;

FIG. 2 is a front elevational view thereof;

FIG. 3 is a rear side elevational view thereof;

FIG. 4 is a left side elevational view thereof;

FIG. 5 is a right side elevational view thereof;

FIG. 6 is a bottom plan view thereof; and,

FIG. 7 is a top plan view thereof.
